GESELLSCHAFT, OF STUTTGART, GERMANY

DYNAMO-ELECTRIC IGNITION APPARATUS

Application filed September 15, 1930, Serial No. 482,116, and in Germany October 7, 1929.

The present invention relates to grounding brushes for the armature windings of dynamo-electric ignition apparatus.

The object of the present invention is to simplify and reduce the expense of the usual earth connection for the rotating winding of dynamo-electric ignition magneto armatures. This earth connection is usually made by means of a carbon brush which is pressed on to a rotating part of the armature, similar to a slip ring, by means of a leaf or spiral spring, the carbon brush being guided in a channel and the current being led off from the carbon brush to earth by a cable.

With carbon brushes which are guided in a channel their free sliding in the said channel becomes gradually more and more restrained by the accumulation of carbon dust especially when the carbon dust mixes with moisture of condensation after the magneto has been in use for a long time.

This difficulty has been overcome by the invention in that the carbon brush is secured without any special guide on a leaf spring pressing it on to the rotating element. The spring is secured to the casing member in a suitable manner and forms part of the current conductor to earth. By this arrangement troubles caused through the accumulation of carbon dust in the usual guides of the carbons are completely eliminated. In addition the cable and earthed securing screw for the same are dispensed with.

The invention is more particularly described with reference to the accompanying drawing which illustrates by way of example one form of construction of the invention and which shows in elevation, a magneto with the distributor disc, distributor gear wheel and the supporting plate with the cam ring and the interrupter removed.

The ignition armature 2 having a slip ring 3 to which is connected one end of the primary winding of the armature, is disposed in the casing 1 of the magneto assembly. A carbon brush 4 which is soldered to the leaf spring 5 slides on this slip ring 3.

The leaf spring which is preferably made

from hard drawn brass is firmly connected to the casing by the screw 6.

What I claim is:

1. Grounding means for an ignition magneto comprising a slip ring carried by the armature of said magneto, a brush cooperating with said ring, and a combined support and grounding element for said brush comprising a spring of blade form in a single arc of curvature approximating the curvature of the slip ring secured at one end to the frame of said magneto and alone supporting said brush from said magneto frame in resilient engagement with said slip ring.

2. Grounding means for an ignition magneto comprising a slip ring carried by the armature of said magneto, a leaf spring secured at one end to the frame of said magneto and in electrical contact therewith, a carbon brush carried by the free end of said spring and supported thereby in resilient engagement with said slip ring, said leaf spring being so formed and so attached to the frame of the magneto as to alone secure said brush in pressure engagement with said slip ring and provide a conductor connection between said brush and the frame of the magneto.

In testimony whereof I have hereunto affixed my signature.

FRITZ ALLENDORFF.
